MUSICAL NOVELTY

Application filed June 29, 1931. Serial No. 547,651.

My invention relates to improvements in musical or rhythmical novelties to be used without or in connection with a special teaching system for encouraging and developing by unconscious finger action a higher technique and musical or rhythmical advancement, particularly in children.

The invention consists of a series of small metal cap-like members, preferably one for each finger and thumb, which are adapted to fit snugly upon the ends of the fingers and thumb in position for convenient tapping with rhythmical effect against any hard or resonant surface.

One of the general objects of the invention is to provide a tapping cap with a plurality of tapping surfaces or portions whereby sounds of different resonant qualities can be produced.

Another object is to so construct the cap-like members that they will snugly and resiliently fit the tips or ends of varying sizes of fingers without constriction and consequent interference with the circulatory system. Another object of the invention is to so construct the cap-like members that they will not interfere with proper finger action.

Further objects and advantages will be apparent as the specification is compared with the accompanying drawing, in which Figure 1 is a pictorial illustration of the musical novelties as used on the fingers of the operator, diagrammatically including a sounding board. Fig. 2 is a rear view of one of the cap-like members used as illustrated in Fig. 1. Fig. 3 is a sectional view on line 3—3 of Fig. 4, and Fig. 4 is a side elevation of the cap-like member, and Fig. 5 a sectional view on line 5—5 of Fig. 4.

Referring more particularly to the drawing wherein I have illustrated a preferred embodiment of my invention, 1 is a substantially U-shaped cap-like member preferably made of thin flexible sheet metal of suitable resilience, and shaped to slip snugly over the end of a person's finger, as illustrated in Fig. 1. The cap 1 comprises a front member or body portion 2, and a back or tongue-like portion or member 3, connected together at one end by a loop portion 4 and extending

substantially parallel with each other in position to grip the ball and back of the finger respectively.

The free end of tongue 3 is provided with a narrow transversely extending arcuate gripping flange 5 of sufficient length to extend approximately across the back of the finger, and a similarly formed but oppositely curved arcuate gripping flange 6 on the free end of the body 2 engages the front of the finger 60 transversely thereof and with resilient gripping effect. Thus the finger will be resiliently gripped between the front and back members 2 and 3 and also between their respective opposing end flanges 5 and 6. These 65 flanges 5 and 6 are preferably made slightly heavier and therefore stronger and less resilient than the tongue 3 as the former are the main gripping and holding surfaces.

The connecting loop 4 comprises a somewhat shallow bulged portion 8 of slightly greater width than the tongue 3, and as previously stated connects the latter to the body 2. The shallow recess 10 formed in the concave side of the bulged portion 8 serves as a 75 seat for the finger tip while a recess 7 formed in the bellied enlargement 9 of the front member 2 seats the ball of the finger.

The bulged portion 8 and enlargement 9 constitute tapping areas and therefore must 80 be comparatively thick and heavy. This is preferably accomplished by crowding the metal from which the cap is made into these areas during the process of stamping, or molding, preferably employed in making the 85 caps. The tongue 3 is relatively thin and of such resilience that it can be flexed to accommodate different sizes of fingers without choking effect.

In practice the extended fingers are manipulated rhythmically with an up and down motion so as to cause the enlargements or tapping areas 9 to contact with a hard surface 10' with musical effect or rhythmical effect. A tapping cap 1 is preferably used on each finger 95 and thumb but practically the same results can be obtained by omitting one or more caps from either hand. If a softer tone is desired the fingers may be slightly curved thus bringing the small bulged portions or tapping areas 100

8 into play. The volume of sound can thus be greatly reduced, because, due to the location of area 8, a slight relative movement of the fingers and cap with respect to each other is caused when the area 8 is brought into play, and this movement serves to cushion the blow. The reduced area and weight of the portion 8, is also a factor in reducing the sound volume as will be obvious.

10 It will be noted that the thumb cap-members 1 are substantially of the same construction as the finger members 1, the only difference being in size and manner of application. The members 1 engage and grip the front and back of the fingers whereas the members 1' engage the sides of the thumb.

15 Due to the inherent resiliency and flexibility of the material used and by virtue of the spring action of the tongue 3, the cap will adapt itself to fingers of different size and 20 will snugly embrace the fingers without choking effect, the gripping flanges being of material aid in preventing objectional longitudinal movement of the cap.

25 Having thus described my invention, what I claim, is:

1. A musical novelty comprising a member of thin flexible material for embracing a person's finger, said member having a plurality 30 of rounded thickened tapping portions formed thereon.

2. A musical novelty comprising a member of hard thin flexible material for embracing a person's finger, said member having a 35 rounded thickened tapping portion.

3. A musical novelty comprising a member of thin hard flexible material for embracing a person's finger, said cap formed with a plurality of rounded thickened portions differing 40 in areas from each other capable of producing sounds of different volume when contacted with a hard surface.

4. A musical novelty comprising a substantially U-shaped member of hard flexible material for embracing a person's finger, said member being open at its sides having a 45 rounded thickened tapping area at its ends.

5. A musical novelty comprising a cap of thin flexible material having front and 50 back relatively parallel members adapted to grip the front and back portions only of a person's finger, a tapping portion connecting said members for seating the finger tip and a thickened bellied enlargement on the other 55 portion for seating the ball of the finger.

6. A musical novelty comprising a cap of thin flexible material having a front bellied tapping portion and a relatively parallel tongue like back portion adapted to grip a 60 person's finger, a tapping portion connecting the outer ends of said front and back portions, and the inner ends of said portions being disconnected from each other.

7. A musical novelty comprising a cap of 65 thin flexible material open at its sides from

end to end and having front and back parallel members, said members being connected together at their outer ends only, a thickened tapping portion on said front member, the free inner ends of said parallel members being formed with transverse finger gripping flanges.

In testimony whereof I affix my signature.

FRIEDRICH J. LANGER.
